P DAFFERN.
AUTOMATIC OIL SUPPLY VALVE.
APPLICATION FILED FEB. 15, 1916.

1.195.188.

Patented Aug. 22, 1916.

PAUL DAFFERN

H. S. Hie

Attorney.

UNITED STATES PATENT OFFICE.

PAUL DAFFERN, OF ROBERT LEE, TEXAS.

AUTOMATIC OIL-SUPPLY VALVE.

1,195,188.

Specification of Letters Patent. Patented Aug. 22, 1916.

Application filed February 15, 1916. Serial No. 78,430.

To all whom it may concern:

Be it known that I, PAUL DAFFERN, a citizen of the United States, residing at Robert Lee, in the county of Coke, State 5 of Texas, have invented a new and useful Automatic Oil-Supply Valve; and I do hereby declare the following to be a full, clear, and exact description of the invention, such as will enable others skilled in the art 10 to which it appertains to make and use the same.

The present invention relates to an automatic oil supply valve, and has for its object to provide a device of this character 15 which embodies novel features of construction whereby the supply of oil or liquid fuel to the burner of a boiler can be controlled automatically by the steam pressure within the boiler.

20 Further objects of the invention are to provide a device of this character which is comparatively simple and inexpensive in its construction, which will enable a uniform steam pressure to be maintained automatically 25 within the boiler, which will not require constant attention from the operator, and which can be adjusted for a high or a low steam pressure, as may be desired.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawing, in which:—

Figure 1 is a side elevation of an automatic oil supply valve constructed in accordance with the invention. Fig. 2 is a vertical sectional view through the same. Fig. 3 is a horizontal sectional view on the line 3—3 of Fig. 2. Fig. 4 is a front elevation of a 45 valve block and carrying frame removed from the valve casing.

Corresponding and like parts are referred to in the following description and indicated in all the views of the drawing by the same 50 reference characters.

Referring to the drawings, which illustrate one embodiment of the invention, the numeral 1 designates a steam cylinder within which a piston 2 is mounted. A 55 steam pipe 3 leading from the boiler communicates with the cylinder 1 toward the

lower end thereof, said lower end being closed by a cap 4 which is provided with a drain cock 5 through which condensed steam can be withdrawn.

A head 6 is screwed upon the upper end of the cylinder 1, and a jam nut 7 is utilized to insure a tight joint between the members. Opposite sides of the cylinder head 6 are formed with the laterally projecting integral ears 8, said ears being provided with openings to receive the threaded extremities of a yoke 9. Nuts 10 are fitted upon the projecting extremities of the threaded ends of the yoke and serve to clamp the yoke 70 rigidly in operative position.

The valve casing 11 is arranged within the yoke 9, being formed with a downwardly projecting stem 11^a which extends through the cylinder head 6 and is threaded within 75 the same. A passage 12 extends transversely through the valve casing 11, and couplings 11^b at opposite ends thereof serve to engage the oil supply pipe sections 13. A vertical opening extends through the valve casing 11 80 and intersects the transverse oil passage 12. A frame 14 is slidably mounted within the vertical opening of the valve casing, being provided with a downwardly projecting rod 15 which extends into the steam cylinder 1 85 and is connected to the piston 2, and also with an upwardly extending rod 16 which has a head 17 loosely mounted upon the upper end thereof. A suitable stuffing box 18 surrounds the rod 16 at the top of the 90 valve casing 11, and a coil spring 19 is interposed between the head 17 of the rod 16 and a similar head 20 on the lower end of a screw 21 which is threaded within the top of the yoke 9. A handle 22 is applied to 95 the upper end of the screw 21 and provides a means for manipulating the same to increase or decrease the tension in the coil spring 19.

A valve block 24 is fitted within the frame 100 14 and formed with a vertical slit 25 through which the oil flows when the valve block is in such a position as to establish communication between the two sections of oil supply pipe 13. As the pressure of steam 105 within the boiler increases, the piston 2 will be forced upwardly against the action of the spring 19, thereby moving the valve block 24 and partially cutting off the supply of oil so that the fire under the boiler will be of 110 decreased intensity. On the other hand, should the steam pressure within the boiler

become decreased, the piston 2 would be forced downwardly by the action of the spring 19 so as to increase the flow of oil to the burner and produce a more intense flame under the boiler. The tension of the spring 19 can be adjusted by manipulating the handle 22, and in this way the device can be set to automatically maintain any degree of steam pressure in the boiler without close attention on the part of the operator.

10 The valve block 24 is fitted removably within the frame 14, being locked in position by suitable means such as the set screws 26. The edges of the valve block may be rabbeted, as indicated at 24^a, to receive packing 27. Rectangular frames 28 may be arranged under the packing and the edges of the valve block may be notched, as indicated at 24^b, to receive springs 29 which act upon the frames 28 to push the packing 27 into operative position on opposite sides of the valve block or slide. A fuel tight joint is thus provided between the slide and the valve casing, and the packing can be readily replaced when it becomes worn. A new valve block or slide 24 can also be readily placed in position at any time, thereby enabling any desired size or shape of aperture 25 to be employed, depending upon the character of the liquid fuel or fluid being employed.

Having thus described the invention, what I claim as new and desire to secure by Letters Patent, is:—

35 1. An automatic liquid fuel supply valve, including a liquid fuel supply pipe, a cylinder, a piston mounted within the cylinder, a valve casing interposed in the length of the liquid fuel supply pipe and mounted upon

the cylinder, a frame slidably mounted within the valve casing and connected to the piston so as to be moved thereby, yielding means opposing this movement of the frame, an apertured valve block fitted within the frame and having rabbeted edges, packing fitted within the said rabbeted edges, and yielding means for holding the packing in operative position, the movements of the apertured valve block serving to control the flow of liquid through the valve casing.

2. An automatic liquid fuel supply valve, including a liquid fuel supply pipe, a cylinder, a piston mounted within the cylinder, a valve casing interposed in the length of the liquid fuel supply pipe and mounted upon the cylinder, a frame slidably mounted within the valve casing and connected to the piston so as to be moved in one direction thereby, yielding means opposing this movement of the frame, a valve block fitted removably within the frame and formed with an aperture for controlling the flow of liquid through the valve casing as the frame and valve block are moved back and forth, said valve block being provided with rabbeted edges and having notches in the sides thereof, packing arranged within the rabbeted edges, and springs arranged within the notches for holding the packing yieldably in operative position on opposite sides of the block.

In testimony whereof I have signed my name to this specification in the presence of two subscribing witnesses.

PAUL DAFFERN.
